UNITED STATES PATENT OFFICE.

FREDERICK C. PALMER, OF SPRINGFIELD, MASSACHUSETTS.

BOLT-ANCHOR.

No. 833,542.

Specification of Letters Patent.

Patented Oct. 16, 1906.

Application filed January 11, 1906. Serial No. 295,545.

To all whom it may concern:

Be it known that I, FREDERICK C. PALMER, a citizen of the United States, residing at Springfield, in the county of Hampden and 5 State of Massachusetts, have invented certain new and useful Improvements in Bolt-Anchors, of which the following is a specification.

My invention relates to bolt-anchors; and 10 its novelty consists in the construction and adaptation of the parts, as will be more fully hereinafter pointed out.

In the drawings, Figure 1 is a side elevation of one of my improved anchors placed in 15 a wall, but not expanded. Fig. 2 is a similar view showing a partial expansion, and Fig. 3 is a similar view showing a double expansion. Fig. 4 is a bottom plan view of the upper half of the parts above the plane of the line 4 4 in 20 Fig. 1. Fig. 5 is a side elevation of one of the shields, and Fig. 6 is a bottom plan view of the same. Fig. 7 is a side elevation of the outer separable bushing. Fig. 8 is a top plan view of the inner separable bushing when one 25 threaded aperture is horizontally placed, and Fig. 9 is a similar view of the same when the other threaded aperture at right angles thereto is horizontally placed. Fig. 10 is a perspective view of the inner bushing. Fig. 11 30 is a central section of the inner bushing, showing a fine-threaded screw engaged therewith; and Fig. 12 is a similar view showing a coarse-threaded screw engaged therewith.

In the drawings, 10 10 are shields, made of 35 any suitable kind of soft metal and cast, stamped, or rolled into shape. Each shield constitutes a longitudinal segment of a cylinder, polyhedron, or similar symmetrical solid. Each tapers slightly outwardly inter- 40 nally at each end 11 11, and each is provided near each end with recesses, notches, or slots 12 12 for the reception of wedges 22 and 33 of separable bushings 20 and 30, respectively, and each shield is also preferably provided 45 with means, as the projections 13 13 and corresponding recesses 14 14, for accurately registering the parts when assembled. These shields may be of any convenient number. I have shown two. It is essential, however, 50 that when assembled they should form a hollow symmetrical sleeve which preferably tapers slightly at 11 11, so that internally its diameter is a little larger at each end than in the center. The internal surface of each 55 shield is preferably smooth or rough, as may be preferred.

20 is a separable tubular bushing adapted to be placed between the shields 10 10 nearest to their outer ends when placed in the wall. It is slightly conical externally, tapering slightly toward its inner end, and may be smooth or threaded internally. It is provided externally with a plurality of wedges 60 22 22, made integral with the body of the bushing or firmly secured thereto. If it is 65 threaded internally, the threads may be cut to two gages in order to engage with bolts differently threaded to correspond.

30 is a second separable tubular bushing adapted to be placed between the shields 10 70 10 nearest to their inner ends when placed in the wall. It is preferably of the form of a cube with rounded truncated corners, so that it will move readily between the shields 10 10. It is threaded, along one axis at 31 to one 75 gage and along a second axis 32 to a second gage, while its two remaining unapertured sides are provided with external wedges 33, arranged in line with its third axis.

40 is a bolt the threads of which are comparatively coarse, and 50 is a bolt the threads of which are relatively fine. The aperture in the bushing 20 should be large enough to permit the free passage of the bolt which is to engage with the threads of the apertures in 85 the bushing 30, so that if the bushing 20 is internally threaded the bolt passing through it will not engage such threads when both bushings are employed.

The manner of using my device is as follows: The parts are first assembled as shown in Fig. 1, the inner and outer tubular bushings being each placed in position so that the wedges 22 and 33 fit into the recesses 12 12, provided for that purpose. It will be found 95 that the bushing 20 will project slightly outward beyond the shields 10 10, as shown in Fig. 1, when the parts are made of the proportions illustrated. If now the bolt 40 is inserted and rotated to hold something against 100 the wall in which the anchor is placed, its threads engage with those of the bushing 30 until its forward rotation is stopped by pressure against the article to be secured. Its further rotation draws back the bushing 30, 105 and as the recess 12 12 at the inner end of the shields and their inner surfaces 11 11 at the same end flare outwardly such rotation presses apart the shields at their inner ends, and therefore holds them firmly against the 110 aperture in the wall in which they have been inserted, as shown in Fig. 2. If now the ro-

tation of the bolt is continued, the bushing 20 comes in contact with the head of the bolt and presses against the inner outwardly-flaring surfaces of the assembled shields 10 5 10 at their outer end. The wedges 22 22 tend to press apart the shields also by reason of their contact with the inclined sides of the recesses 12 12. The parts finally assume the position illustrated in Fig. 3, and the bolt is 10 firmly held in position against the object to be secured by reason of such double expansion. This does not, however, exhaust the usefulness of the device. By turning the bushing 30 a quarter of the way around the 15 second threaded aperture having threads 31 is presented for engagement with another bolt 50, threaded to fit the same. By supplying a number of these double-apertured bushings the same shields may be used with 20 a large number of differently-threaded bolts, each bushing being adapted to serve with two of such bolts provided with threads of different standards. Moreover, the bushing 30 may be taken out entirely and the shields 25 reversed in position, leaving in the bushing 20. In such case if a bolt adapted to engage with the threads of the bushing 20 is used it may be used therewith efficiently, and if threaded to two gages two sizes of standard 30 threads may be employed with it. The bushing 30 may also be used alone with bolts provided with threads of different gages. By

the use of my device, therefore, one set of shields may be used with bolts of three sizes, and by the use of additional double-threaded 35 bushings its capacity can be much increased.

What I claim as new is—

1. In a device of the kind described, comprising separable shields, a tubular bushing adapted to be inclosed by the shields and 40 threaded (to engage bolts or screws) in the lines of different axes.

2. In a device of the kind described, comprising separable shields, a tubular bushing adapted to be inclosed by the shields and 45 threaded (to engage bolts or screws) in more than one direction with threads of different standards.

3. A tubular bushing for a bolt-anchor of substantially cubical form with truncated 50 corners and threaded in apertures along two of its axes.

4. A tubular bushing for a bolt-anchor of substantially cubical form with truncated corners and threaded in apertures along two 55 of its axes and provided externally along its third axis with wedges.

In testimony whereof I affix my signature in presence of two witnesses.

FREDERICK C. PALMER.
